(57) **CLAIM**

The ornamental design for an absorbent sheet dispenser, as shown and described.

DESCRIPTION

FIG. 1 is a top, front and left side perspective view of a dispenser showing our new design;

FIG. 2 is front elevational view thereof;

FIG. 3 is a side elevational view from the right of FIG. 2, the side elevational view from the left of FIG. 2 being the mirror image thereof;

FIG. 4 is a top plan view thereof; and,

FIG. 5 is a bottom plan view thereof.

The dashed lines represent rolls of absorbent sheet material positioned within the dispenser in use, and are not claimed. The appearance of the rear surface of the dispenser is not claimed.
